UNITED STATES PATENT OFFICE.

HENRY FINCK, OF NEW YORK, N. Y.

DESIGN FOR A RUG.

SPECIFICATION forming part of Design No. 16,314, dated October 6, 1885

Application filed August 28, 1885. Serial No. 175,607. Term of patent 34 years.

To all whom it may concern:

Be it known that I, HENRY FINCK, a citizen of the United States, residing at New York, in the county and State of New York, have invented and produced a new and original Design for a Rug; and I do hereby declare that the photographic print accompanying this specification conveys to any one skilled in the art a clear understanding of the same, and is sufficient to enable such persons to use my invention.

The leading features of my design consist in a triple-panel center. The middle panel is ornamented by the representation of a peacock with spread plumage, and a conventional florid ornamentation at each side and bottom of the panel.

The end panels are each ornamented by a

conventional florid ornamentation, and the whole is surrounded by an ornamental border, as shown in the photographic print accompanying this specification.

I claim—

The design for a rug, the same consisting of a triple-panel center, the middle panel ornamented by the representation of a peacock with spread plumage, and a conventional florid ornamentation at each side and bottom of the panel, in combination with end panels ornamented by a conventional florid representation, and the whole surrounded by an ornamental border, as shown and described.

HENRY FINCK.
